UNITED STATES PATENT OFFICE.

ARTHUR S. FOREMAN, OF ST. PAUL, MINNESOTA.

PLATEN-PRESS CHASE-LOCK.

1,078,137.

Specification of Letters Patent. Patented Nov. 11, 1913.

Application filed March 27, 1913. Serial No. 757,149.

To all whom it may concern:

Be it known that I, ARTHUR S. FOREMAN, a citizen of the United States, residing at 558 St. Peter street, in the city of St. Paul, 5 county of Ramsey, and State of Minnesota, have invented a new and useful Platen-Press Chase-Lock, of which the following is a specification.

My invention relates to a method of locking or securing chases upon the bed of 10 platen printing presses, and the objects of my invention are, first, to provide for the use upon such presses of chases of smaller size than those made for use with the press; 15 second, to provide facilities for the adjustment of the apparatus to enable chases of varying size to be used upon a single platen printing press. I attain these objects by the mechanism illustrated in the accompanying drawing, in which:

Figure 1 is a view of the entire apparatus. For the purpose of more definite illustration, this view represents the apparatus as it would appear with a chase locked in 25 it. Fig. 2 is a detailed sectional view of the device for locking the chase at its top.

The outer frame (a), beveled at its lower outer corners and at its top (bbb) constitutes the framework of the apparatus. This 30 frame is beveled on the inner side of its lower bar (f) in such manner as to receive and hold securely the chase to be used, by engaging the beveled edge of such chase, in the manner shown in Fig. 1, where the 35 beveled edge of the chase is secured in the beveled mortise in the bar (e) at (gg). An adjustable bar (e) terminating in V-shaped lugs (d) about one-half the thickness of the bar, extends horizontally across the 40 lower portion of the frame, and is secured by the lugs at its ends entering corresponding mortises (ee) in the frame. When the apparatus is locked on the press, the bar rests upon the press bed and the portion 45 of the frame which extends over the mortises (ee) secures the desired amount of rigidity. This bar contains mortises of varying length and depth (gg) to engage the beveled edges of the various sizes of 50 chases to be used. When necessary to secure greater latitude of adjustment, I would have an additional mortise or mortises on the lower side of the bar at (hh). The bar may be adjusted by placing its ends at the 55 desired point in the series of beveled mor-

tises (ee) in the frame, or by turning end for end and bringing the desired mortise in position to engage the chase to be used.

A locking device to secure the chase at its top is incorporated in the upper bar of the 60 frame. I prefer to carry out this feature of my invention in the manner shown in Fig. 2, where it will be seen that a movable clutch (i) operating in a mortise in the frame, moves as if at the circumference of 65 a circle corresponding to the curvature of its longest side. The lower beveled end of this clutch is forced down upon and secures the chase by the action of a spring (k) contained in a mortise in the frame and connected with the clutch by a rod which passes through the clutch and frame in a channel of sufficient size to prevent the rod binding by reason of the rotary motion of the clutch, this rod being secured to the clutch at (l) 70 by a pivotal fastening. The clutch is operated to permit the insertion or removal of a chase when the apparatus is on the press, by a projection (m) accessible by a slot in the frame as shown. The movement of the 75 clutch is restricted to the desired extent by this projection engaging the ends of the slot. When necessary to secure other adjustments of the apparatus, I would incorporate this locking device in a bar to be secured and adjusted across the upper portion 80 of the frame at (n) in the same manner in which the lower bar is secured and adjusted; that is, by means of the adjustment of its ends in a series of mortises in the frame. 85

As a means of securing sidewise adjustment of the chase upon the press bed, I would continue the bevels (ff) and (gg) in the lower bar of the frame (a) and in the adjustable bar (e) respectively, the entire 95 width of the frame and bar, and provide against sidewise movement of the chase by means of two pegs or screws adjustable in a series of holes in the frame or bar in such manner as to engage the chase on either side 100 and prevent sidewise movement.

I claim:

1. A platen press chase lock, comprising a rigid frame mortised to engage the locking device of the press, a semi-circular locking device actuated by a spiral spring, contained in the frame central of its upper side, and a lower cross bar adjustably engaged in notches in the sides of the frame, substantially as described. 110

2. In a platen press chase lock, the combination of a rigid frame, mortised to engage the locking device of the press, having a series of V-shaped notches in its vertical sides, covered by approximately one-half the structure of said sides, beveled along its lower inner edge to engage the beveled edge of a platen press chase, and containing a recess central of its upper side in which is 5 contained a semi-circular locking device actuated by a spiral spring to engage the beveled edge of a platen press chase, and a lower cross bar, beveled on its upper and lower edges to engage the beveled edge of varying 10 sizes of platen press chases, and adjustably secured in the V-shaped notches in the vertical sides of the frame, and reversible; all substantially as described, for the purpose specified.
- 15 3. In a platen press chase lock, the com-

binaton of a rigid frame, mortised to engage the locking device of the press, having a series of V-shaped notches in its vertical sides, covered by approximately one-half the structure of said sides, beveled along its 25 lower inner edge to engage the beveled edge of a platen press chase, and containing a recess central of its upper side, in which is contained a semi-circular shaped locking device actuated by a spiral spring to engage 30 the beveled edge of a platen press chase, and a cross bar, adjustably secured in the V-shaped notches in the sides of the frame; all substantially as described, for the purpose specified.

ARTHUR S. FOREMAN.
